UNITED STATES PATENT OFFICE.

GEORGE M. PETTENGILL, OF HAVERHILL, MASSACHUSETTS, ASSIGNOR TO HAMEL SHOE MACHINERY COMPANY, A CORPORATION OF MASSACHUSETTS.

HEEL-NAILING MACHINE.

1,425,540.

Specification of Letters Patent. Patented Aug. 15, 1922.

Application filed June 4, 1918. Serial No. 238,087.

To all whom it may concern:

Be it known that I, GEORGE M. PETTENGILL, a citizen of the United States, residing at Haverhill, in the county of Essex and 5 State of Massachusetts, have invented certain new and useful Improvements in Heel-Nailing Machines, of which the following is a specification, reference being had therein to the accompanying drawings.

10 This invention relates to certain improvements in heel nailing machines in which means is provided for applying cement or glue to a heel lift preparatory to the nailing operation and more particularly to improvements in a cement-applying device such as is illustrated in the patent to Pettengill, 1,156,850, October 12, 1915.

In mechanisms of the above type, the top lift to which cement is to be applied and which is thereafter "spanked" onto the projecting heads of the heel-attaching nails, is placed by the operator in a suitable holder carried by the reciprocating cross head of the machine. As the cross head descends, the top lift thus held moves down into contact with the surface of a suitable cement-applying roll and in wiping over the same becomes coated with cement. The roll employed is supported for free turning movement in a cement pot or container and is caused to turn by frictional contact with the top lift as the latter wipes thereover thus keeping the surface of the roll constantly coated with cement. In the patented device a pawl and ratchet is employed 25 to prevent retrograde movement of the roll which might occur on the upward movement of the cross head by contact of parts carried thereby with the roll.

The arrangement above described operates 40 in an entirely satisfactory manner when top lifts of usual sizes are employed, but it is found in practice that when the machine is operating upon the small lifts employed in connection with heels of the "Louis" type, 45 the frictional engagement thereof with the cementing roll is insufficient always to insure rotation of the latter, the viscosity of the cement into which the roll dips exerting a braking action thereon which it requires an appreciable force to overcome.

The invention provides a cementing attachment for use with nailing machines of that type employing a reciprocating cross head provided with a top lift holder, said attachment comprising a rotary cement-applying member and means independent of said top lift holder and having connection to said cross head for intermittently rotating said cement-applying member.

Other and further objects and advantages 60 of the invention together with new and improved details of construction will be hereinafter more fully described and particularly pointed out in the claims, reference being had to the accompanying drawings 65 for a full disclosure of a preferred embodiment thereof and in which,—

Fig. 1 is a front, diagrammatic elevation of so much of the upper portion of a heel nailing machine as is necessary to illustrate 70 the application of this invention thereto, the cross head being shown as at the upper limit of its stroke,

Fig. 2 is a plan view of the attachment to enlarged scale, and

Fig. 3 is a side elevation, partly in section, of the attachment, to the same scale as in Fig. 2, illustrating the arrangement of the operating mechanism, the parts occupying the position which they assume at the lower limit of movement of the cross head.

1 indicates a portion of the main frame of the machine provided with suitable guideways for a pair of vertically slidable rods 2, of which only one is illustrated, said rods having mounted upon their upper ends a vertically reciprocable cross head 3. 4 is a turret rotatably mounted upon the cross head, said turret providing a pair of divergent arms 5 and 6, carrying at their respective outer extremities a top-lift holder 7 and a driver member 8. The turret is further provided with a pair of spaced apart notches 9 and 10 adapted for engagement by a slidable bolt 11 whereby the turret may be locked in position with either the top-lift holder or the nail driver in position for operation. The above described mechanism is all of a character well known in the art, and further detail description thereof is therefore unnecessary.

As herein shown a top-lift tray 12 is fixed to the frame member 1 at a convenient point thereon, said tray being provided at its inner extremity with a downwardly depending lug 13, to which a horizontally disposed arm 14 is pivotally connected. 14^a is a rod depending from the tray 12 and passing through an opening in the arm 14, said rod being provided with a head upon its lower extremity and having a spring 14^b interposed between said head and the arm 14, whereby said arm is resiliently supported in proper position. The arm 14 is provided at its free extremity with a socket 15 in which is adjustably mounted a standard 16 carrying at its upper extremity a receptacle 17 for holding cement or glue for application to the surface of a heel lift. 18 and 19 are bosses formed upon the opposite ends 20 of said receptacle, said bosses being provided with aligned, threaded openings in which are mounted a pair of oppositely directed screw-threaded pins 20, 21 which may be held in proper adjusted position by means of lock nuts, if desired. Said pins 20 and 21 are so formed at their opposite extremities as to provide pintle bearings for a shaft 22 freely rotatable thereon, the shaft 22 constituting a support for a roll 23 the surface of which may be covered with felt or other suitable material, as illustrated at 24.

The shaft 22, as herein shown, is screw threaded throughout its length, and has mounted thereon near one end a collar 25 serving to position the roll 23 thereon, the roll being held in fixed relation to the shaft and against said collar by means of a nut 26. 27 is a ratchet wheel herein shown as integral with the collar 25, said ratchet wheel being adapted for engagement with the pawl 28 fixed to the cement-holding receptacle, this pawl and ratchet being provided to prevent retrograde movement of the roll 23.

The device thus far described is similar in character to that shown in the patent to Pettengill, above noted, and is capable of operation in the same manner, it being noted, however, that under certain circumstances the device as thus constructed fails to function properly.

29 is a lug formed upon the rear portion of the cement receptacle, said lug having pivoted thereon a bell-crank lever 30 having arms 31 and 32. Pivoted to the arm 32, as by means of a pin 33, is a pawl 34, said pawl being guided within a slot 34 formed in the upper edge of said cement receptacle, and having its free extremity 35 shaped to engage the teeth of a second ratchet wheel 36 fast to the shaft 22 and adjacent the wheel 27. As herein shown, said wheels 27 and 36 and the collar are integral, but it is clearly evident that it is within the scope of the

invention to form said elements independently and to fix them to the shaft in any desired manner. The receptacle 17 may, if desired, be provided with an adjustable stop member 30^a for engagement by the arm 31 of bell crank 30 to limit the downward movement of the same.

37 is a rod connected at the point 38 to the free extremity of the arm 31 of bell crank 30, said rod being guided at its upper portion by passing through an opening 39 in a stud 40 projecting outwardly from the forward face of the cross head 3. The upper extremity of rod 37 is screw threaded, as shown at 41, for the reception of the nut 42 which may be held in adjusted position by means of a suitable lock nut. Interposed between nut 42 and the stud 40 is a coil spring 43, the upper extremity of which is connected, in any desired manner, to the nut 42, this, however, not being essential, as it is permissible to allow this spring to slide freely upon the rod 37.

The operation of the above mechanism is as follows, the parts being initially positioned as shown in Fig. 1. Preparatory to the nailing stroke of the cross head, the holder 7 is provided with a top lift in the usual manner, and as the cross head moves downwardly such top lift in descending 95 wipes over the surface of the felt-covered roll 23 causing the latter to rotate and at the same time coating the surface of the top lift with the cement carried by said roll. The frictional engagement of the top lift 100 with the roll is usually sufficient to turn the roll thereby to provide the roll with a fresh coating of the cement after each operation. During such movement of the roll the pawl 34 will move freely over the ratchet teeth 105 of the wheel 36, and at the same time the pawl 28 will move over the teeth of the ratchet 27.

When employing top lifts of very small size, it is sometimes found that the frictional 110 engagement of the same with the roll is insufficient to turn the latter to the proper amount to insure a fresh coating of the cement upon the felt covering thereof, and the devices constituting the present invention 115 operate in the following manner to overcome this difficulty. As the cross head moves downward, the stud 40 carried thereby also moves downwardly permitting the rod 37 to drop to a slight extent, carrying 120 with it the bell-crank lever 30 and retracting the pawl 34, the parts thus moving until the bell-crank lever is stopped by engagement of arm 31 with stop member 30^a, whereupon stud 40 continues its downward 125 movement sliding freely on rod 37.

Upon upward movement of the cross head the stud 40 will engage the lower extremity of spring 43 just prior to reaching the upward limit of its stroke and will thus, 130

through compression of the spring, cause an upward movement of rod 37, thereby turning bell-crank lever 30 and moving pawl 34 forwardly to cause a partial rotation of the 5 roll 23. The roll is thus caused, upon each up-stroke of the cross head, to move a sufficient distance to insure a proper coating thereof with cement, this action being entirely independent of the size or thickness 10 of the top lift carried by the top-lift holder.

It will be observed that the attachment 15 constituting the present invention does not in any manner interfere with the operation of the roll as described in the above noted patent to Pettengill, but forms merely an auxiliary device adapted, under certain circumstances, to insure proper turning of the roll whereby to provide the latter with a constant and uniform supply of cement.

20 It is to be understood that various modifications and changes in the structure shown could be made without departing from the present invention, the embodiment of the invention herein illustrated being shown by 25 way of example and not by way of limitation.

The term "heel lift" employed in the appended claims is intended to cover either an entire heel or any part thereof as it will be 30 obvious from the above description that many features of the present invention may be embodied in a device for applying cement to entire heels as well as to the top-lifts thereof.

35 Having now thus described the invention and a preferred embodiment thereof, together with the mode of operation of the same what I claim and desire to secure by Letters Patent of the United States is,—

40 1. In a heelng machine, a vertically reciprocating heel-lift holder adapted to support a heel-lift in a position oblique to the vertical and facing downward, a cement-applying device arranged directly in the 45 path of movement of the lift as it is carried downward in said position by the holder, and means independent of said lift, for insuring a constant supply of cement to said cementing device.

50 2. In a heelng machine a vertically reciprocating cross head and a turret mounted thereon having an arm provided with a heel-lift holder at its end arranged to hold the lift at right angles to said arm, means 55 for locking the turret in a position in which said arm extends obliquely downward, a rotatable cement applier mounted directly beneath said holder in position to be engaged by the lift held thereby on downward movement of the cross head and means independent of said lift for rotating said cement applier.

60 3. In a heelng machine a vertically reciprocating carrier having a heel-lift holder 65 movably mounted thereon, and means for

locking said holder in position to hold a lift with one side oblique to the vertical and facing downward during a downward movement of the carrier, a cement receptacle and a roll mounted to rotate therein about a horizontally disposed axis and beneath a lift held by said holder in position to be engaged by the lift during such downward movement, and means independent of said lift, for intermittently rotating said roll. 75

4. In a heel nailing machine, a vertically reciprocating carrier having a heel lift holder mounted thereon, a cement receptacle, a roll mounted to rotate therein about a horizontally disposed axis and beneath a lift held by said holder and in position to be engaged by said lift upon downward movement of the carrier, a ratchet fast to said roll, a pawl engageable with said ratchet, and means connected to said carrier for actuating said pawl to impart a movement of rotation to said roll on upward movement of said carrier. 80

5. In a heel nailing machine having a reciprocating cross head, a heel-lift holder 90 carried by the cross head, a relatively fixed cement receptacle having a cement-applying roll rotatably supported therein, a ratchet wheel fast to said roll, a pivotally supported lever member, a pawl connected to one end 95 of said lever member and engageable with said ratchet wheel, and means connecting the other end of said lever member with the cross head whereby movement of the latter serves to rotate said roll. 100

6. In a heel nailing machine having a reciprocating cross head, in combination, a relatively fixed cement receptacle, a cement-applying roll rotatably mounted therein and provided with a ratchet wheel fixed thereto, 105 a bell-crank lever mounted upon said receptacle, a pawl pivoted to one arm of said lever and engaging said ratchet, a rod having operative engagement with the other arm of said lever and means carried by the 110 cross head for reciprocating said rod.

7. In a heel nailing machine having a reciprocable cross head, in combination, a cement-applying device mounted to rotate in relatively fixed bearings and means for intermittently rotating said device comprising a stud projecting from said cross head and having a guide opening therein, a rod 115 slideable in said guide opening, a nut having screw-threaded engagement with the free extremity of said rod, and resilient means tending to move said nut away from said stud. 120

8. In a machine of the class described having a reciprocating element, in combination, a relatively fixed fluid container, a fluid-applying roll rotatably supported within said container, a ratchet fixed to said roll, a pawl engaging said ratchet, and means for actuating said pawl for rotating 125 130

the roll comprising a lever having one arm thereof pivotally connected to the pawl, a rod having one end thereof connected to the other arm of said lever, a stud projecting from said reciprocating element and provided with a guide opening for said rod, an

extremity of said rod, and a coiled spring surrounding said rod and located between said stop member and said stud.

In testimony whereof, I have signed my name to this specification.

GEORGE M. PETTENGILL.
